UNITED STATES PATENT OFFICE.

DAVID E. SANDBERG, OF DETROIT, MICHIGAN.

ADJUSTABLE DETACHABLE ROD AND FIXTURE SUPPORT.

1,345,463.

Specification of Letters Patent.

Patented July 6, 1920.

Application filed April 24, 1919. Serial No. 292,275.

To all whom it may concern:

Be it known that I, DAVID E. SANDBERG, a citizen of the United States, and a resident of the city of Detroit, in the county of Wayne and State of Michigan, have invented certain new and useful Improvements in Adjustable Detachable Rod and Fixture Supports; and I do hereby declare that the following is a full, clear, and exact 10 description of the same, reference being had to the accompanying drawings, and to the numerals of reference marked thereon, which form a part of this specification.

This invention relates to an improved type 15 of support comprising brackets attachable upon any suitable projecting member, such as the back of a chair or the projecting molding board of a wall, so that the device when attached may be utilized as a supporting 20 means for bath room fixtures or other articles.

It is an object therefore of this invention to construct an improved rack or support 25 adapted to be connected upon any suitable object, thus providing a support for mounting different articles or objects, spaced from the object upon which the rack is connected.

It is also an object of this invention to 30 construct a rack comprising bracket arms in which a supporting rail is mounted, said arms adapted to be connected upon an object and provided with adjustable clamping 35 brackets whereby the entire device is held rigidly connected upon the object for support thereby.

It is furthermore an object of this invention to construct a rack for attachment upon a wall or article of furniture to provide a 40 supporting rail or rod spaced therefrom comprising brackets adapted to engage in clamping relation upon the article of furniture or wall member, as the case may be, to hold the rack rigidly supported thereon.

It is finally an object of this invention to 45 construct an improved type of rack simple in construction and operation and readily adjusted for connection upon an article of furniture or other means to support the rack in position for use in supporting bath- 50 room or other similar fixtures.

Other and further important objects of this invention will be apparent from the disclosures in the specification and drawings.

The invention (in a preferred form) is 55 illustrated in the drawings and hereinafter more fully described.

On the drawings:

Figure 1 is a front elevational view of a wall molding having removably mounted thereon a plurality of fixture supports, embodying the principles of my invention. 60

Fig. 2 is an enlarged sectional view taken on line 2—2 of Fig. 1, showing parts in elevation.

Fig. 3 is a rear elevation of a supporting 65 bracket.

Fig. 4 is a front elevation thereof.

Fig. 5 is a top plan view of the bracket showing a fragmentary sectional portion of a rod supported thereby. 70

Fig. 6 is a bottom plan view of the supporting bracket.

Fig. 7 is a reduced view taken on line 7—7, of Fig. 2.

As shown on the drawings: 75

The reference numeral 1, indicates the wall or any other object or article on which a transverse member, molding or board 2, is mounted or secured. The rod or fixture support consists of a pair of adjustably connected angled clamps or brackets, the upper or main bracket embracing an upright portion 3, with the upper end thereof bent rearwardly at an angle as denoted by the reference numeral 4, and provided with engaging 80 teeth or wedges 5. The lower portion of the upper bracket is bent outwardly at an angle to form an extension or arm 6, which is directed oppositely to said portion 4, though substantially parallel thereto, and at its 85 outer end is provided with an eye 7, in which one end of a curtain or towel rod 8, is engaged. An aperture or opening 9, is provided near the outer end of the extension portion 6. Each upper bracket near the 90 junction of the portions 3 and 6, thereof is provided with a circular aperture through the arm portion 6, through which a bolt 10, is inserted, having a rounded screw head 11.

The lower or auxiliary bracket comprises 100 an upright portion 12, with the lower portion thereof turned at an angle thereto, as denoted by the reference numeral 13, and provided with engaging teeth or wedges 14. The upper portion of the lower bracket is 105 bent outwardly to provide the arm or extension 15, which is provided with an aperture through which the lower end of said bolt 10, engages. A squared nut 16, is threaded on the lower end of said bolt 10, 110 and is prevented from rotation on the bolt by contact with the upright portion 12, of

the auxiliary or lower bracket. Adjustment of said upper and lower brackets with reference to one another is obtained by rotation of the bolt 10, by means of any suitable tool 5 engaging the screw head 11, thereof.

Figs. 1 and 2, show a support adapted to serve as a mounting means for a bathroom fixture wherein the reference numeral 17, indicates a cup holder which is seated upon the bracket arm 6, and is held in position by the upper end of a screw bolt 18, which projects through the arm opening 9, and through the apertured center of the cup holder as shown in Fig. 2. A lock nut 19, is provided on the bolt 18, for holding the cup holder securely in place. The bolt 18, extends downwardly and has engaged on the lower end thereof a notched or slotted disk or plate 20, for holding tooth brushes.

Fig. 1, also shows the support adapted for use as a supporting means for a U-shaped frame or hanger 22, on which a roll of paper 21, is rotatably mounted.

The operation is as follows:

The support when used is mounted upon the transverse molding 2, or on any other suitable means, by engaging the portion 4, of the upper or main bracket, over the upper edge of the member 2, and wedging the teeth 5, into engagement therewith or between the member 2, and the wall 1, as the case may be. The upper bracket is thus supported in a manner to sustain loads placed upon the rail or rod 8, one end of which passes through the eye 7, of said upper bracket. A similar support is of course, provided for supporting the other end of the rod 8. A further means is provided for holding the upper bracket rigidly 40 attached in position so as to increase the supporting strength thereof. This is gained by the use of the lower or auxiliary bracket which is engaged along the under edge of the transverse member 2, in a similar manner to which the upper bracket is engaged over the upper edge thereof. The connecting bolt 10, engaging said respective upper and lower brackets is provided, to draw said respective brackets toward one another in 50 clamping relation upon the article or object on which the device is attached.

As shown in Figs. 1 and 2, the apertured arm 6, of the support is adapted to readily afford a means permitting the cup holder 17, and the tooth brush plate 20, to be mounted 55 in position for use in a bath room or in any other place desired.

The improved support is also readily adaptable to serve as a convenient support for a roll of paper, the supporting frame 60 22, of which, may be engaged in the eye 7, of the upper bracket of the support. The improved supports may be used for numerous other purposes, such as supports for a glass shelf 23, as shown in Fig. 1. Curtain 65 rods may also be conveniently supported by a pair of supports of the class described.

I am aware that numerous details of construction may be varied through a wide range without departing from the principles 70 of my invention and I therefore do not purpose limiting the patent granted further than necessitated by the prior art.

I claim as my invention:

1. A bathroom fixture support comprising 75 a pair of apertured clamping members, gripping means integrally formed thereon to engage a supporting molding, means projecting through said clamping members adapted to draw the same together to securely clamp said molding, an apertured arm integrally formed on one of said clamping members, and an eye formed on the end of said arm, said arm and eye adapted to support bathroom fixtures thereon in position for use.

2. A fixture support comprising an angled member adapted to engage a supporting molding, an apertured horizontal projecting arm formed integrally on the angled member, and an eye on the outer end of the horizontal arm, formed by bending the outer end of said arm downwardly and inwardly, said eye adapting the support to engage a 90 rod.

In testimony whereof I have hereunto subscribed my name in the presence of two 95 subscribing witnesses.

DAVID E. SANDBERG.
